UNITED STATES PATENT OFFICE.

WILLIAM E. VAN DORN, OF CHICAGO, ILLINOIS.

METAL CAR END.

Application filed November 20, 1920, Serial No. 425,316. Renewed July 13, 1923.

To all whom it may concern:

Be it known that I, WILLIAM E. VAN DORN, a citizen of the United States, residing at Chicago, county of Cook, State of Illinois, have invented a certain new and useful Improvement in Metal Car Ends, and declare the following to be a full, clear, and exact description of the same, such as will enable others skilled in the art to which it pertains to make and use the same, reference being had to the accompanying drawings, which form a part of this specification.

My invention has for its object to produce a simple and novel sheet metal car end which may easily be applied and which will make the end of a car body very strong with a minimum weight of material.

The various features of novelty whereby my invention is characterized will herein after be pointed out with particularity in the claims; but, for a full understanding of my invention and of its object and advantages, reference may be had to the following detailed description taken in connection with the accompanying drawings, wherein:

Figure 1 is an elevation of one-half of a metal end for a box car arranged in accordance with one form of my invention;

Fig. 2 is a section taken approximately on line 2—2 of Fig. 1;

Fig. 3 is a vertical section taken approximately on line 3—3 of Fig. 1;

Fig. 4 is a view similar to Fig. 1, showing the other half of the end together with the associated parts for attaching it to the adjacent side of the car body;

Fig. 5 is a section taken approximately on line 5—5 of Fig. 4;

Fig. 6 is a perspective view of the interior of one corner of a car body having a sheet metal end somewhat different from that shown in Figs. 1 to 5;

Fig. 7 is a horizontal section taken through the structure shown in Fig. 6;

Figs. 8, 9 and 10 are views similar to Fig. 7, illustrating still other modifications;

Fig. 11 is a perspective view of one end of a gondola car embodying the present invention, portions being broken away to expose other portions which would otherwise be hidden;

Fig. 12 is a transverse horizontal section through that portion of the car shown in Fig. 11, on an enlarged scale;

Fig. 13 is an end view of a car embody-

ing my invention in another form, both the floor frame and roof structure being shown;

Fig. 14 is a side elevation of that end of the car shown in Fig. 13; and

Fig. 15 is a section taken approximately on line 15—15 of Fig. 13.

Referring to the first five figures of the drawings, 1 and 2 represent two sheet metal plates each of the full width of the car body, the plate 1 being adapted to form the lower half of the car end and the plate 2 the upper half. The two plates are joined together in any suitable way as, for example, by means of a lap joint, 3, in which a bottom marginal portion of the upper plate overlaps a top marginal portion of the lower plate and is riveted thereto. The car end thus formed may be shaped in any suitable way at the top and at the bottom for attachment to the floor and roof structures. A flat marginal portion, 4, is provided at each side edge or side of the metal end, the space between these flat marginal portions containing transverse corrugations which, in the arrangement shown, completely fill this space. The ends of the corrugations are flattened as indicated at 6, so that all the ends thereof at one side of the car lie in a single vertical plane forming an angle, preferably an acute angle of about forty-five degrees with the plane of the sheet. The metal end may be attached to the car body in the manner illustrated in Figs. 4 and 5, in which 7 represents one of the side walls of the car body, terminating in a corner post, 8, which, broadly speaking, may be said to be a part of the side wall. Lying against the flattened ends of the corrugations is a vertical reinforcing bar, 9, which, in the arrangement shown, is a comparatively wide plate bent so as to overlie the adjacent flat marginal portion 4, extend beyond the latter, and then continue around the corner so as to overlap the end of the side wall as indicated at 10; the reinforcing bar being preferably fastened to each flat corrugation end by means of rivets, 11, and being also attached to the adjacent flat marginal portion of the sheet by means of rivets, 12. On the inner side of the side wall of the car are any desired number of straps, 13, each of which has one end, 14, shaped to fit within one or more of the corrugations and lie against the inner face of the flattened end or ends thereof. The other end of each of the straps

100
105
110

preferably extends to or beyond one of the side wall posts 7^a and is secured thereto by bolts, 13^a, as illustrated in Fig. 6. The ends, 14, of the straps may conveniently be fastened in place by means of the rivets 11, the latter passing through the member 9, through the flattened corrugation end, and through the part 14. Transverse bolts, 15, may pass through the member 13, the corner post and the flange, 10, on the reinforcing bar. The straps may be continued inwardly for any desired distance and in any desired direction.

It will be seen that the flattening of the ends of the corrugations permits the formation of a post-like arrangement transversely to the corrugations and at the ends thereof, so as greatly to stiffen the structure. At the same time these flattened ends provide excellent seats for attachment of plates or bars serving to attach the metal end to the sides of the car body.

It will be seen that the reinforcing bars pass directly over the lap joint between the two sheets, thus giving added strength to the connection between the two sheets.

In Figs. 6 and 7 I have illustrated a structure slightly different from that shown in Figs. 1 to 5, the flat marginal flange, 16, of the corrugated sheet, 17, being bent inwardly or rearwardly at right angles to the plane of the sheet so as to lie against the inner side of the corner post, 8. The reinforcing bar, 18, is substantially the same as the bar 9, while the plates, 13, on the inner side of the side wall of the car body are the same as the corresponding plates in the other form. The bolts, 15, in this instance pass through the member 13, the flange 16, the post 8 and the flange 10 on the reinforcing bar.

In Fig. 8 the flat marginal side portion, 19, of the corrugated sheet, 20, is made wide enough so as to be flanged around the outer side of the corner post, as indicated at 21. The reinforcing bar, 22, is angle-shaped in cross section, lying against the flattened ends of the corrugations and the adjacent portion of the flat margin, 19, being secured to the former by the rivets, 11, and to the latter by rivets, 23.

In Figs. 1 to 8 the corrugations in the metal end are shown as being directed wholly outwardly from the normal plane of the sheet. My invention is of course not limited to this particular arrangement but is applicable to sheets in which the corrugations are directed inwardly, in part or in whole, from the normal plane of the sheet. Thus, in Fig. 9 there is shown a construction in which the corrugations, 24, are directed inwardly, from the normal plane of the sheet, 25, the flat marginal side portion, 26, being in the normal plane. The vertical reinforcing bar, 27, should in this instance be placed on the inside so as

to avoid the necessity of forming ears or projections along one edge for entry into the corrugations, as would be necessary if the reinforcing bar were placed on the outside. In the construction shown, 70 the reinforcing bar is roughly V-shaped in cross section, one flange, 28, thereof lying against the flattened ends, 6, of the corrugations and being riveted thereto by means of rivets, 29, while the other flange, 30, lies 75 against the inner side of the post 8. The flat marginal portions at the sides of the sheet may be connected to the sides of the car body in any suitable way. In the arrangement shown, the part 26 is carried 80 around the corner post as indicated at 31, in much the same way as in Fig. 8. If desired, straps, 32, corresponding to the straps 13 in the other forms may extend inwardly along the sides of the car body from the reinforcing bar; suitable bolts, 33, passing through the flange 30 of the reinforcing bar, through the ends of the straps 32, the post and the flange 31, serving to unite the various parts 85 of the car body.

In Fig. 10 there is shown an arrangement similar to that in Fig. 9 adapted for use in a car body in which the side wall, 34, does not terminate in a corner post. The metal end itself, and the reinforcing bar are substantially the same as in Fig. 9, but the holding plates, 35, are bent away from the side wall as they approach the end wall, so as to lie approximately at right angles to the plane of the flattened ends of the corrugations, being then bent back upon themselves so that their extreme end portions, 36, lie parallel with said plane; there being rivets, 37, passing through the flattened ends, 6, the overlying flange of the reinforcing bar, and the parts 36 of the holding straps.

In Figs. 11 and 12 there is illustrated a simple end construction for gondola cars, the metal end being made of a single corrugated sheet, 40, having flat marginal side portions, 41, extended inwardly and lying against the inner faces of the side walls, 42, of the car body. The reinforcing plates, 43, lie against the flat ends of the corrugations, are continued outwardly across the 115 end edges of the side walls of the car body, and are then flanged, as indicated at 44, so as to engage the outer faces of the side walls of the car body. The reinforcing plates are riveted to the end sheet by means 120 of suitable rivets, 45, while bolts, 46, pass through the flat marginal portions 41, the flanges 44, and the car sides interposed between these elements. Along the upper edges of the sides and ends of the car body 125 is a bulb angle plate, 47, one of whose flanges is vertical and the other horizontal and extends outwardly; the vertical flange, 48, of the member 47 lying behind the upper marginal portion of the sheet 40,

In the arrangement shown in Figs. 13 to 15, the metal end is made up of three horizontal panels, 51, 52 and 53, secured together by suitable lap joints, 3. The flat marginal portions at the sides of the panels are flanged around the corners of the car body as indicated at 54. Each corner is reinforced by means of a vertical reinforcing bar, 55, having one flange or wing lying 5 against the flattened ends, 6, of the corrugations and the other flange or wing lying against the flat marginal portion immediately adjacent to the ends of the corrugations. The reinforcing bar may be attached 10 to the corner post by means of bolts, 56, passing through the reinforcing bar, the underlying flat marginal portion of the metal end, and the post. If desired, the inner marginal portion of the reinforcing bar, as indicated at 57, may extend beyond 15 the flattened ends of the corrugations and overlie the undeformed portions of the corrugations adjacent to the flattened ends; rivets, 58, passing through the part 57 of 20 the reinforcing bar and the high portions of the corrugations, serving to fasten the bar rigidly to the several panels. As in the arrangement shown in Fig. 1, the reinforcing bar at the corner extends over the lap joints 25 between the several panels. The upper end of the reinforcing bar is carried high enough to permit it to be attached to the roof structure, conventionally indicated at 59, by means of suitable bolts, 60, independently of 30 the fastenings for the upper panel of the metal end. Similarly, the lower end of the reinforcing bar is carried down past the end sill, 61, of the floor frame of the car and it is bolted to this end sill independently 35 of the panels. In the arrangement shown, the lower end of the reinforcing bar extends behind an angular corner plate, 62, one wing or flange of which lies against the front face of the end sill and the other wing 40 or flange of which extends across the end of the end sill. Bolts, 63, passing through the front flange or wing of the member 62, the lower end of the reinforcing bar, and the end sill, fasten these elements securely together. 45

Added stiffness may be given to the corner by placing within the same an angle iron post, 64, one flange of which lies against the corner post, 8, and the other against the inner surface of the sheet metal end. One flange of the post 64 may be riveted to the sheet metal end while the other may be fastened to the post, conveniently by means of bolts, 65, passing through the same, through 50 the post, and through the flange 54 on the metal end. The bolts, 65, may also pass through the outer ends of reinforcing straps, 66, extending inwardly along the side of the car from the end. 55

While I have illustrated and described

only a single form of my invention with slight modifications, I do not desire to be limited to this particular form or to the particular type or arrangement of corrugations illustrated; but intend to cover all 70 forms and arrangements which come within the terms employed in the definitions of my invention constituting the appended claims.

I claim:

1. A sheet metal car end having flat marginal portions at two of the sides and provided between said flat marginal portions with a plurality of corrugations extending transversely of said marginal portions and merging into each other so that the sheet 75 has a sinuous configuration transversely of the corrugations, the ends of the corrugations being flattened so the corresponding ends thereof on each of said sides of the sheet lie in a plane making an acute angle 80 with the plane of the sheet.

2. A sheet metal car end having transverse corrugations terminating in the vicinity of the sides of the sheet, said corrugations merging into each other so that the 90 sheet has a sinuous configuration transversely of the corrugations the ends of the corrugations being flattened so that corresponding ends thereof on each side of the sheet decrease gradually in depth and lie 95 in a vertical plane making an angle with the plane of the sheet.

3. A sheet metal car end having transverse corrugations terminating in the vicinity of the sides of the sheet, the ends of 100 the corrugations being flattened so that corresponding ends thereof on each side of the sheet lie in a vertical plane making an angle with the plane of the sheet, and a vertical reinforcing bar lying against and secured to said flattened ends at each end of 105 the corrugations.

4. A sheet metal car end having transverse corrugations terminating in the vicinity of the sides of the sheet, said corrugations merging into each other so that the sheet has a sinuous configuration transversely of the corrugations the ends of the corrugations being flattened so that corresponding ends thereof on each side of the 110 sheet lie in a vertical plane making an acute angle with the plane of the sheet.

5. A sheet metal car end having at the sides marginal portions bent at an angle to the plane of the sheet for attachment to the side face of a car body side or post, together with transverse corrugations extending from the vicinity of one of said marginal portions to the vicinity of the other, said corrugations merging into each other so that the sheet has a sinuous configuration transversely of the corrugations the ends of said corrugations being flattened so that the corresponding ends thereof at 115 each side of the sheet decrease gradually

- in depth and lie in a vertical plane forming an angle with the plane of the sheet.
6. A sheet metal car end having at the sides marginal portions bent at an angle to the plane of the sheet for attachment to the side face of a car body side or post, together with transverse corrugations extending from the vicinity of one of said marginal portions to the vicinity of the other, the ends of said corrugations being flattened so that the corresponding ends thereof at each side of the sheet lie in a vertical plane forming an angle with the plane of the sheet, and a vertical reinforcing bar lying against and secured to said flattened ends at each end of the corrugations.
7. In combination, a car body having sides and a sheet metal end, said sheet metal end having flat marginal portions at the sides engaged with the adjacent parts of the car body sides and having transverse corrugations extending between said marginal portions, the ends of said corrugations being flattened so that the corresponding ends thereof at each side of the sheet lie in a vertical plane making an angle with the plane of the sheet, and vertical reinforcing bars secured respectively to said flattened ends and to the car body sides.
8. In combination, a car body having sides and a sheet metal end, said sheet metal end having flat marginal portions at the sides engaged with the adjacent parts of the car body sides and having transverse corrugations extending between said marginal portions, the ends of said corrugations being flattened so that the corresponding ends thereof at each side of the sheet lie in a vertical plane making an acute angle with the plane of the sheet, and vertical reinforcing bars secured respectively to said flattened ends and to the car body sides.
9. In combination, a car body having sides and a sheet metal end, said sheet metal end having flat marginal portions at the sides engaged with the adjacent parts of the car body sides and having transverse corrugations extending between said marginal portions, the ends of said corrugations being flattened so that the corresponding ends thereof at each side of the sheet lie in a vertical plane making an acute angle with the plane of the sheet, and metal pieces secured respectively to said flattened ends of the corrugations and to the said car body sides.
10. In combination, a car body having sides and a sheet metal end, said sheet metal end being made of a plurality of transverse panels each having transverse corrugations, the ends of said corrugations being flattened so as to lie in a vertical plane making an angle with the plane of the sheet, and vertical reinforcing bars extending continuously from top to bottom of said metal end and secured respectively to the flattened ends of the corrugations and to the car body sides.
11. The combination with the side walls of a car body having side wall posts, the floor frame and the roof structure of a car body, of a sheet metal end flanged at the sides to engage with the side faces of the side walls of the car body and having transverse corrugations decreasing gradually in depth at their ends to flatten the latter, anchoring straps riveted at one end to the flattened ends of the corrugations and extending inwardly along the side walls of the car body to said side wall posts, and means for securing said straps to said posts.
- In testimony whereof, I sign this specification.

WILLIAM E. VAN DORN.
